The ornamental design for a multisided shower bar, as shown and described.

DESCRIPTION

FIG. 1 is a side view, all sides being the same, of a first embodiment of the multisided shower bar showing our new design;

FIG. 2 is an end view thereof, the opposite end being the same, taken along the lines 2—2 of FIG. 1;

FIG. 3 is a cross-section view thereof taken along the lines 3—3 of FIG. 1;

FIG. 4 is a side view, all sides being the same, of a second embodiment of the multisided shower bar showing our new design;

FIG. 5 is an end view thereof, the opposite end being the same, taken along the lines 5—5 of FIG. 4;

FIG. 6 is a cross-section view thereof taken along the lines 6—6 of FIG. 4;

FIG. 7 is a side view, all sides being the same, of a third embodiment of the multisided shower bar showing our new design;

FIG. 8 is an end view thereof, the opposite end being the same, taken along the lines 8—8 of FIG. 7;

FIG. 9 is a cross-section view thereof taken along the lines 9—9 of FIG. 7;

FIG. 10 is a side view, all sides being the same, of a fourth embodiment of the multisided shower bar showing our new design;

FIG. 11 is an end view thereof, the opposite end being the same, taken along the lines 11—11 of FIG. 10;

FIG. 12 is a cross-section view thereof taken along the lines 12—12 of FIG. 10;

FIG. 13 is a side view, all sides being the same, of a fifth embodiment of the multisided shower bar showing our new design;

FIG. 14 is an end view thereof, the opposite end being the same, taken along the lines 14—14 of FIG. 13;

FIG. 15 is a cross-section view thereof taken along the lines 15—15 of FIG. 13;

FIG. 16 is a side view, all sides being the same, of a sixth embodiment of the multisided shower bar showing our new design;

FIG. 17 is an end view thereof, the opposite end being the same, taken along the lines 17—17 of FIG. 16;

FIG. 18 is a cross-section view thereof taken along the lines 18—18 of FIG. 16;

FIG. 19 is a side view, all sides being the same, of a seventh embodiment of the multisided shower bar showing our new design;

FIG. 20 is an end view thereof, the opposite end being the same, taken along the lines 20—20 of FIG. 19;

FIG. 21 is a cross-section view thereof taken along the lines 21—21 of FIG. 19;

FIG. 22 is a side view, all sides being the same, of an eighth embodiment of the multisided shower bar showing our new design;

FIG. 23 is an end view thereof, the opposite end being the same, taken along the lines 23—23 of FIG. 22; and,

FIG. 24 is a cross-section view thereof taken along the lines 24—24 of FIG. 22.
